ATTORNEY.

UNITED STATES PATENT OFFICE.

WILLIAM E. NYE, OF HIGHLANDS, CALIFORNIA.

VULCANIZING-PATCH-HOLDING DEVICE.

1,283,275.

Specification of Letters Patent. Patented Oct. 29, 1918.

Application filed August 20, 1917. Serial No. 188,517.

To all whom it may concern:

Be it known that I, WILLIAM E. NYE, a citizen of the United States, residing at Highlands, in the county of San Bernardino 5 and State of California, have invented certain new and useful Improvements in Vulcanizing-Patch-Holding Devices, of which the following is a specification.

This invention relates to improvements in 10 vulcanizing patch holding devices and especially to that class of devices designed to hold a self heating patch container which is, adapted to vulcanize tire tubes, water bottles and the like, the fuel for curing the rubber 15 in said patch being carried by the said container.

It is an object of this invention to construct a patch holding device that is in the 20 form of a pair of tongs and having a head with arms projecting therefrom which is provided with gripping means for securely holding the patch container while the said patch is properly placed upon the article to be repaired.

25 It is a further object of this invention to provide an instrument used in connection with vulcanizing which is in the form of a pair of pivotally connected members, one of which members is provided with a head 30 adapted to securely hold the patch container, the holding means comprising a spring gripper or magnetic arm secured to said head, while the other member is provided with a plate for holding the article to be vulcanized.

35 It is also an object of this invention to provide a locking means, which is simple but effective, whereby the tongs may be securely held in closed position after the patch 40 has been properly placed for vulcanizing.

With these and other objects in view, the invention comprises certain novel constructions, combinations and arrangements of parts, as will be hereinafter more fully described and claimed.

In the accompanying drawing forming a part of this specification:

Figure 1 is a side elevation of the patch holding device showing a patch clamped 50 upon an inner tube, certain parts being shown in section.

Fig. 2 is a partial plan view of the patch holding device.

55 Fig. 3 is a front elevation of the patch holding device partially shown in section

and the patch container shown in dotted lines held by the head of said device.

Fig. 4 is a bottom view of the spidered head showing the patch container in dotted lines.

60 Fig. 5 is a front elevation of a modified form of the device representing a patch container in dotted lines as being held in place magnetically.

Fig. 6 is a section taken on line 6—6 of Fig. 5.

70 The device forming the subject matter of this invention is designed for use in connection with vulcanizing and particularly for holding a vulcanizing patch container while 75 the same may be placed upon an article to be repaired. The form of the device shown is that of a pair of tongs 10, which have a pair of handles 11 and 12 and are pivotally connected at 13. The handles 11 and 12 80 have extensions 14 and 15, which preferably extend beyond the pivot point 13 and provide means for extending over the article to be repaired. At the outer end of the extension 14 is a pivotally attached head 16 85 adapted to have a slight swinging movement about the pivot point 17. At the lower end of the head 16, spider arms 18, 19 and 20 are provided and have a seat portion as 21 adapted to rest upon the container. Formed 90 at the outer end of the extension member 15 is a plate 22, this plate being preferably oblong in form and situated directly under the spider arms, thereby registering therewith when the tongs are closed, so that the 95 article resting upon the said plate will be in the proper position to receive the patch, which is mounted upon the patch container 24. The head 16 is provided with a gripper member 25, which is preferably in the form 100 of a spring and extends along the upper surface of the arm 18 and has its ends 26 bent downwardly forming grippers, and adapted to extend into grooves 27 formed in the ends of the arm 18. The gripper ends 105 26 securely hold the patch container upon the spidered arms and allow an operator using the tongs to place the said tongs upon the article to be vulcanized without any danger of dropping the said container from 110 the head of the device. The arm 20 is provided with a stop or downwardly extending projection 28 which centers the patch container over the said plate when the tongs are closed.

110

It will be necessary to provide means whereby the head will not swing out of position with relation to the said plate, and a spring 29 is provided which seats against the under surface of the extension 14 and the gripper member 25, thereby insuring a perfect alinement of the head member and plate. The arms 11 and 12 are provided with a lock 30 which is pivoted on the arm 12 at 31, and has a head 32 adapted to engage notches 33 secured in the upper edge of the arm 11. This lock provides means whereby the patch will be securely clamped upon the article to be repaired, and obviates any danger of the said patch getting out of place.

The modified form shown in Figs. 5 and 6 has substantially the same head and spidered arm shown in Fig. 1. In this form of the device, there is no spring gripping member to grip the edges of the patch container. The arms 34 and 35 are of such material, preferably of steel, which will receive a charge of magnetism, thereby forming a magnet of the said arms 34 and 35. The patch container is made of metal and when placed upon the magnetic arms, is held thereby and centered over the plate 36 by downwardly projecting stops or detents 37 formed at the ends of the arms 34 and 35.

A spring 38 which holds the head and magnetic arm in proper position with respect to the plate, rests against the lower edge of the extension 14 and the upper surface of the said arms and allows a proper adjustment of the head member when the patch is clamped upon the article to be repaired.

It will be observed that the device is so constructed that the patch device may be quickly inserted into the head of the tongs and held thereby, so that the operator of the device may handle the tongs with one hand and adjust the article to be vulcanized with

the other hand, thereby eliminating any danger of misplacing the said patch.

It will be understood that the details of the device may be varied, and mechanical equivalents substituted therefor, without departing from the spirit of the invention.

What is claimed is:

1. A vulcanizing patch holding device comprising a pair of tongs pivoted together and having handle extensions on one end and clamping extensions on the other end thereof, a patch holding plate on the clamping extension of one of said members, and a head pivotally supported in registration with said head on the clamping extension of said other member, said head having a pair of transverse arms and a pair of longitudinal arms formed thereon, one of said arms having a depending extension for engagement with the patch holder, and a spring supported on said head and having its ends extended at opposite points therebelow and for resilient engagement with and for holding said patch holder in position.

2. A vulcanizing patch holding device comprising a pair of pivoted tongs, one of said tongs having a plate thereon, a head pivotally supported on the other of said tongs opposite said plate, an elongated spring seated in the center of said head, and having its ends extended below said head for engagement with a patch holder.

3. A vulcanizing patch holding device comprising a pair of pivoted tongs, provided with a stationary plate, and a resiliently yieldable head, a rigid depending extension on one side of said head, and a right angularly disposed spring having extensions below said head between which, and said rigid extension a patch holder is adapted to be held in operating position.

WILLIAM E. NYE.
